Fig. 4

FIG. 1 is a top plan view of a soft surface floor covering showing my new design, a complete unit being shown, the unit repeating in a corner to corner relationship, as indicated by the matching top and bottom and the matching sides;

FIG. 2 is a cross sectional view taken on line 2—2 of FIG. 1;

FIG. 3 is an enlarged fragmentary view of a portion of FIG. 1; and

FIG. 4 is a cross sectional view taken on line 4—4 of FIG. 3.

The backing surface opposite to that shown in FIG. 1 is a conventional planar backing without ornamentation.

I claim:

The ornamental design for a soft surface floor covering, as shown and described.
